ACOUSTICAL CORRECTION MACHINE

Milton S. Wunderlich, International Falls, Minn.,
assignor to The Insulite Company, Minneapolis,
Minn., a corporation of Minnesota

Application December 15, 1938, Serial No. 245,873

2 Claims. (Cl. 144—110)

This invention pertains to betterments and improvements in the acoustical correction of rooms, halls, auditoriums, and the like, and involves the use of means for forming perforations or apertures extending into the wall surface, particularly of walls having sound absorbing material covering the surfaces thereof whereby the sound waves passing into the surface are absorbed or dissipated. One object of the invention is to provide an apparatus which will form perforations or apertures in the ceilings and thereby provide a sound absorbing construction of high efficiency and one which at the time will afford a surface which may be decorated in the usual way without interfering with the sound deadening properties.

Another aim of the invention is to afford a procedure by which walls and the like may have openings formed into or through the surface in situ, prior to decoration or after decoration of the wall surface.

The present invention has a superiority over the prior art of giving the sound absorbing wall surfaced rooms the required acoustical correction needed in the particular enclosure.

Other and further objects of the invention will appear in the course of the following description and the invention resides in the novel features and the combination of parts which will be particularly used in the claims.

This invention is capable of numerous forms and variations without departing from the essential features herein disclosed. It is, therefore, the intent and desire that the embodiment shown herein be deemed illustrative and not restricted, and that the patent shall cover all features of patentable novelty existing in the invention disclosed, reference being had to the claims rather than to the specific description herein to indicate the scope of the invention.

In the drawings forming part of this application similar characters of reference indicate corresponding parts in all the views.

Fig. 1 is a view in elevation of the new improved acoustical drilling machine.

Fig. 2 is a top plan view of the drill head.

Fig. 3 is the side elevational view of the drill head.

Fig. 4 is a view taken on lines 4—4 of Fig. 1.

Fig. 5 is a sectional view taken on line 5—5 of Figure 1.

Fig. 6 is a modified form of the acoustical drilling machine.

Fig. 7 is a side elevational view of the drill head shown in Fig. 6.

Fig. 8 is a view taken along lines 8—8 of Fig. 6. Fig. 9 is a sectional view with part of the drill head broken away.

Referring to the drawings in detail the acoustical perforating machine includes a base 10 which may be and preferably is supported by ball bearing rollers 11. Secured to the base 10 is frame 12, which is so constructed that a source of power such as an electrical motor 14 may be located within frame 12. The motor 14 is secured to a dish-shaped member 15 which is fastened to the base 10. Secured to the upper end of frame 12 is a hollow casing member 13. Movably supported in member 13 is a tubular casing 16 which is provided near one end thereof with rack teeth 17. Pinion 18 is adapted to engage rack teeth 17 for the purpose of permitting raising and lowering of the drill head, hereinafter to be most specifically described. Handle 19 is adapted to be secured to the pinion 18 and this handle should be of sufficient length that the raising and lowering of the drill head may be accomplished with comparative ease. Telescopically secured in member 16 is an upper tubular casing 20. Casing 20 can be secured in the adjusted positions by suitable means such as a bolt and nut 21. Drill head 22 is supported by casing 20 and carried by the upper plate 23 of the drill head 22, are guide members 24. Operatively encircling portions of members 24 are elastic tension members such as springs 25. The extent to which members 24 can be compressed are controlled by threaded adjusting bolts 26. Secured to casing 16 at the upper end of member 13 is shoulder member 27. To the drive shaft 28 the upper end of which is hollow to receive the square solid end of the upper drive shaft 29. Suitably located within the supporting casings 16 and 20 are bearings such as 30.

Operation.—Specifically, by way of example, the acoustical correction of any room may be accomplished in the following manner: for example, ceiling 32 or any enclosure has applied thereto sound absorbing material 33 such as vegetable fiber board. When it has been determined the amount of acoustical correction required for the enclosure and the location in the room where such correction is required the drilling apparatus is adjusted to the desired or required height so that the drilling of the ceiling may be easily accomplished. The operator after locating the drilling head in the proper position applies force downwardly on handle 19 which results in the forcing upwardly and in contact with the mate-

rial to be perforated, drills of head 22. When handle 18 is forced downwardly, the casings 16 and 20 are forced upwardly, thus carrying the head 22 toward the ceiling. The depth to which the material is perforated is controlled by members 24, springs 25 and bolts 26.

In Fig. 6 is shown a modified form of the acoustical drilling machine. This form is particularly adapted for drilling in corners, around lights and various other structures in which the form shown in Fig. 1 could not readily be used. The form shown in Fig. 6 consists of base 10 supported by suitable rollers 11. Supported by base 10 is telescoping casings 35 and 36 and the height to which the stand are to be used can be adjusted and secured in the adjusted position by member 37. Support member 35 is secured rigidly in member 38 which is preferably formed integral with member 40 and these together with member 39 form a hinge member which is adapted to pivot on shaft 41. This shaft 41 extends through hinge member 42 which enables the upper portion of the drill stand to be moved without the necessity of moving the base 10. Shaft 44 is secured to the base 10 and likewise secured to the hinge member 42. The upper end of supporting member 36 is provided with tubular member 45 which is suitably secured to frame 46 at 44a. The spaced apart members 46 are secured together by members 47 and secured to members 41 and 46 are supporting rods 48 and 49. Secured to the upper end of 49 is drill head support 50 for supporting the drill head 22. The drill head may be identical with that used and shown with apparatus disclosed in Fig. 1.

For guiding and properly locating the drill head 22, a rod 51 is secured to member 49 and is provided with handle 52 at the lower end thereof. Member 48 has secured at the upper end thereof supporting platform 53 which is adapted to rest and be secured to power transmitting device 54 which may be an electrical motor. This motor 54 is adapted to drive the drill through the medium of drive belt 55 and drive pulley 56. Drive pulley 56 is operatively secured to stub shaft 57 and the upper end of stub shaft 57 is secured to gear 58 which is adapted to enmesh in operative condition with gears 60 which in turn drive gears 61 and 62 and thereby the drills 65 are caused to revolve. In the form of acoustical drilling machine shown in Fig. 6 it is essential that the operator be able to force the drill head against the material to be perforated and this may be accomplished by securing to the frame 46, a rod 55 chain or other means 67. The rod 67 is secured

to the frame 46 at 66. A handle member 69 is pivotally secured to the casing 35 at 68, and rod 67 is secured to the handle member 69 at 70.

The operation of this form of the drilling machine is very similar to that of the form shown in Fig. 1, therefore, a description of the operation of the machine is deemed to be unnecessary.

The number of drills to be carried by head 22 may be varied and depends in part upon the area that it is desired to treat.

While fiber board has been shown as the sound absorbing material it is to be understood that various plasters may be used and the plaster perforated if desired. In the case of fiber board plaster base the perforations may extend through the plaster and into the base.

It will be obvious to those familiar with sound insulating materials that effectiveness of my new system of acoustical treatment is in the penetration of the sound waves into the opening formed where the energy is dissipated in the sound absorbing material.

The drills or perforating means are preferably so arranged that they revolve in the opposite direction to screw direction of the drill. The direction of rotation of the perforating means forces into the wall substantially all of the material removed from the wall surface and does not permit it to escape into the room.

What I claim is:

1. A drilling apparatus for perforating sound absorbing material in situ including a drill head having a cover plate, a plurality of drills operatively mounted in the drill head and passing through the cover plate, adjustable means for supporting the drill head, movable means for feeding the drills into work, a plurality of substantially U-shaped means mounted on said plate near the edges thereof for engaging the work during drilling for aiding in positioning the drills and limiting the feeding means, and means for driving the drills.

2. In an acoustical drilling machine the combination of a drill head having a substantially rectangular cover plate, a plurality of drills in the head and passing through the cover plate, an adjustable drive shaft for operating the drills; means for rotating the drive shaft, means for feeding the drills into the work, and four independent operating stop means carried by the drill head and engaging the work during drilling, one of said stop means positioned each side of the drill head near the edge thereof.
